UNITED STATES PATENT OFFICE

100,219

DESIGN FOR A STORAGE BATTERY CONTAINER

Joseph G. Monnin, San Leandro, Calif.

Application May 16, 1936, Serial No. 62,683

Term of patent 7 years

To all whom it may concern:

Be it known that I, Joseph G. Monnin, a citizen of the United States, residing at San Leandro, in the county of Alameda and State of California, have invented a new, original, and ornamental Design for Storage Battery Containers, of which the following is a specification.

Referring to the accompanying drawing which constitutes a part of the specification;

The figure is a perspective view of a storage

battery container showing my new design. That side and end of the container not illustrated are substantially identical in design to the side and end shown.

I claim:

The ornamental design for a storage battery container substantially as shown and described.

In witness whereof, I have hereunto subscribed my name.

JOSEPH G. MONNIN.
